WIRE STRETCHER

Application filed May 2, 1929. Serial No. 359,948.

This invention relates to wire stretchers and particularly to wire stretchers having the form of a lever adapted to be placed at one end against a post or other support, the stretching power being applied to the other end of the lever and provided with wire or cable gripping jaws.

The general object of our invention is to provide a particularly powerful and effective stretcher so constructed that it has a positive grip on the wire, the wire gripping means being of such character and so connected that the greater the strain applied on the handle, the greater will be the gripping action of the jaws, the release of pressure on the handle or lever causing the jaws to positively free themselves from engagement with the wire, chain or cable.

A further object of the invention is to provide a device of this character having a star-shaped element adapted to be disposed against the support and rocked thereon, thus doing away with the necessity of using chains or rods to fasten the stretcher to the post or other support, thus permitting the stretcher to be used more effectively and more readily than other wire stretchers known to us.

A further object is to provide a stretcher of this character having a handle and a fixed jaw thereon, a rocking jaw associated with the fixed jaw and a terminal member pivoted to the handle inward of the fixed jaw and carrying the movable jaw, the terminal member in turn at its extremity being so formed as to have rocking, nonslipping engagement with the post, the rocking of the terminal member under strain acting to close the movable jaw at one end against the like end of the fixed jaw.

Other objects will appear in the course of the following description.

Our invention is illustrated in the accompanying drawing, wherein:

Figure 1 is a plan view of a wire stretcher constructed in accordance with our invention;

Figure 2 is a plan view showing the manner in which the wrench is used, the post being in section;

Figure 3 is a section on the line 3—3 of Figure 1, the handle being in elevation;

Figure 4 is a section on the line 4—4 of Figure 1.

Referring to this drawing, 10 designates the handle or lever which is of heavy iron, flattened at one end as at 11 to form a shank and this flattened portion being longitudinally extended and terminating in a transversely extending cross head 12 recessed at 13 upon its front face to render the cross head lighter in weight, this cross head being formed to provide the oppositely disposed jaws 14 which are slightly rounded upon their inner faces, that is, the faces confronting the extremity of the handle 10.

These rounded faces are transversely serrated. The cross head 12 is slotted as at 15. Extending through this slot is a flat shank 16 gradually increasing in width toward the handle, which shank carries upon it the cross head 17 confronting the cross head 12 and recessed upon its front face. A bolt 18 passes through this cross head and through the flattened portion 11 of the handle and carries a nut 19 and washer 20, the washer bearing against the rear face of the handle portion 11 and the nut bearing against the washer in an obvious manner. The extremities of the cross head 17 are formed to provide jaws 21, these jaws confronting the jaws 14 and the jaws being slightly concave upon their faces confronting the jaws 14 and being transversely serrated as at 22. When one of these jaws 21 is turned toward or against the jaw 14, the serrated concave portion 22 approximately fits the curvature of the inner face of the jaw 14. The slot 15 is, of course, large enough to permit the shank 16 to rock sufficiently to cause one or the other of the jaws 21 to bear against one or the other of the jaws 14.

The stretcher is made of heavy iron or steel and obviously the exact form of the stretcher might be modified from that shown without departing from the spirit of the invention as defined in the appended claims.

In the use of the stretcher all that is necessary is to open the jaws, lay the wire within the space between the jaws and place the arcuately curved toothed end 16^a of the ele-

ment 16 against the fence post or other support, that is, against the side or back of the post.

Pressure is then applied to the handle. 5 This will cause the element 16 to rock upon the handle so that it is disposed at an angle thereto which will bring the jaws close together and the greater the pressure applied to the handle under these circumstances, the 10 greater the pressure which the closed jaws exert upon the wire cable or other object gripped thereby. When once a grip has been secured upon the wire, the operator may lay his body against the handle, leaving both 15 hands free to handle staples and the hammer. The greater the pressure applied upon the handle, the greater the gripping action upon the jaws and when pressure is released on the handle, the jaws will free themselves 20 from the wire.

With this wire stretcher, it is possible to stretch the wire to the corner post and have no slack left as is necessarily the case where a rope block or other like stretcher is used, the 25 reason being that the fulcrum upon which this stretcher acts is behind the post, that is, on the side of the post in a direction away from the point at which the wire is anchored and this stretcher may be pulled around the post to 30 any desired extent to cause the wrapping of the wire partially around the post. This is due to the fact that the arcuately arranged teeth 16^a permit a rotation of the handle through at least 180°. In any position of 35 these arcuate teeth 16^a, the points of one or more teeth will enter into the wood of the post, thus securing a firm non-slipping engagement with the post at all times.

One of the strong points of this stretcher resides in the fact that the movable cross head 40 17 is placed back of the stationary jaw 12. By this crossing effect of the jaws we get the tension on the pull side or front of the stretcher, whereas if the movable jaw was in 45 front of the stationary jaw, when pressure was applied to the handle, the stretcher would roll over and release the wire. With our stretcher, the pull coming in front, it is absolutely impossible for it to roll and release 50 the wire. It will under all circumstances stay in proper alinement. Thus for instance, if the handle extended out past the fixed jaw 12 and the terminal member 16 were pivoted to this handle outwardly of the fixed jaw in 55 stead of being pivoted inward, then with pressure applied to the handle in the direction shown in Figure 2, for instance, the grip would be on the opposite side of the handle from the work and this would tend to turn or 60 roll the wire stretcher around and release the jaw. The construction is such that it would be entirely possible to drop forge this stretcher, making slight changes in it to this end without, however, departing from the spirit 65 of the invention.

We have illustrated the jaws as being formed by riveting the lateral extensions of the jaws to the cross heads of the shanks 11 and 16 by means of rivets 23. We have also shown the bolt 18 as shouldered so as to prevent it clamping the terminal member 16 and keeping it from working free.

We claim:—

1. A wire stretcher of the character described, comprising a handle, a stationary cross head on one end of the handle and having a serrated jaw facing toward the other end of the handle, the cross head being slotted, a shank extending through said slot, the shank at its inner end carrying a transversely extending cross head formed with a jaw confronting the first-named jaw, the cross head being pivoted to the handle for oscillation, the shank at its end remote from its pivot being formed with an arcuate series of teeth. 75

2. A wire stretcher of the character described, comprising a handle carrying at one end an outwardly projecting cross head, the cross head extending transversely of the length of the handle and at its ends and on its inner face being serrated to provide jaws, the cross head being slotted, a shank extending through the slot of the cross head, the shank at its inner end being formed with a cross head, the extremity of this cross head being formed with jaws confronting the first named jaws, a pivot bolt passing through the second named cross head and shank and through the handle, the extremity of the shank away from the cross head being formed with an arcuate series of post engaging teeth. 90

3. A wire stretcher comprising a handle flattened toward one end, the flattened end of the handle being formed with an outwardly projecting transversely extending cross head, the cross head at its ends and on its inner face being formed with rounded transversely serrated jaw surfaces, the cross head being slotted, a shank extending through said slot and pivoted to the flattened portion of the handle for rocking movement, the pivotal end of the shank having a transversely extending cross head formed to provide jaws confronting the jaws of the first named cross head, 105 said jaws being transversely concave and serrated, the outer extremity of the shank being formed with radiating post engaging teeth. 110

4. A wire stretcher comprising a handle 120 formed with a flattened portion and a cross head rigid with the flattened portion and projecting laterally beyond the same, the inner faces of the cross head being rounded and transversely serrated, the cross head being slotted, a shank extending through the slot in the cross head and pivoted to the flattened portion of the handle whereby the shank may oscillate, the pivotal end of the shank being provided with a cross head 125 130

formed with jaws confronting the first named jaws and transversely serrated, the extremity of the shank being formed for rocking engagement with the post.

5. A wire stretcher of the character described comprising a handle, a stationary cross head mounted upon the handle and having a jaw facing toward the handle, a shank pivoted to the handle and at its inner end carrying a transversely extending cross head formed with a jaw confronting the first-named jaw, the shank at its outer end being formed to engage against a fixed abutment.

10 In testimony whereof we hereunto affix our
15 signatures.
